METHOD OF MAKING FINGER RINGS

William E. Eccles, Owatonna, Minn., assignor to
 The Josten Manufacturing Company, Owatonna, Minn., a corporation of Minnesota

Application December 29, 1936, Serial No. 118,112

4 Claims. (Cl. 29—160.6)

This invention relates to the manufacture of finger rings constructed of two different metals, usually gold and silver, or high and low-carat gold, or gold and a base metal; and its objects are to simplify and expedite the required operations, to obtain effective control of the amount of gold and silver contained in the completed ring, and to make possible the use of relatively thin sheets of the precious material.

10 In the accompanying drawing, Fig. 1 is a perspective view of a gold blank. Fig. 2 illustrates in full lines two gold end-pieces and in dotted lines an intervening silver filler piece. Fig. 3 is a perspective view of the silver filler piece. Fig. 4 is a perspective view showing the silver filler piece and the two gold end-pieces secured to the gold blank illustrated in Fig. 1. Fig. 5 is a sectional view taken through the parts shown in Fig. 4, but after those parts have been subjected to the action of the two dies indicated in dotted lines in Fig. 5. Fig. 6 is a perspective view of the stamping produced by the operation indicated in Fig. 5. Fig. 7 is a fragmental sectional view of said stamping, on a larger scale. Fig. 8 is a perspective view of the stamping shown in Fig. 6 after it has been trimmed and its flat side milled. Fig. 9 is a perspective view of a gold lining plate. Fig. 10 shows, in full lines, a longitudinal central section through the parts represented in Figs. 8 and 9 after the gold lining plate has been secured to the flat side of the part illustrated in Fig. 8. Fig. 10 also shows in dotted lines the form of the parts after they have been bent into ring form.

25 For the sake of brevity, I shall use the term "gold" to denote any relatively costly metal or alloy, and the term "silver" to denote any relatively cheap or base metal or alloy.

In producing a finger ring by the method hereinafter disclosed, I form the blank 1 by punching it from a thin sheet of gold stock, such sheet being a stock article of commerce. The dies used in the punching operation are relatively inexpensive as compared with forming dies. The blank 1

40 consists of a central portion 2 and two end portions 3 extending in opposite directions from the central portion and in substantially the same plane. If desired, a central opening 4 may be formed in the portion 2, to reduce the amount of gold. The opening 4 may be of various shapes and sizes.

The silver which is to be enclosed within the gold exterior of the ring is in the form of a filler piece 5 consisting of a middle portion 6 having a

45 central hump or generally rounded elevation 7.

The outline of the middle portion and its height and shape may vary. At each end of the middle portion 6 is a relatively slender portion 8.

That part of the finger band which is at the inner side of the finger is to be solid gold. For this reason, two end-pieces 9 formed of gold are secured to the ends of the portions 8 of the filler piece by soldering, welding or fusing. The width of the end-pieces 9 corresponds generally to the width of the slender portions 8 of the filler piece. As shown in Fig. 4, the width of the end-pieces 9 and the filler piece 5 is less than that of the blank 1, so that the projecting edge portions of the blank 1 may be formed up to enclose the edges of the parts 5 and 9.

15 The unit composed of the parts 5 and 9 is then secured to the blank 1 in any desired way, as by soldering, welding or fusing, as shown in Fig. 4, to form a composite blank which, for convenience of description, will be referred to as the blank 10. If desired, the end pieces 9 may be secured to the blank 1, and the filler piece 5 then secured to the blank 1 between the end pieces.

20 The next step consists in stamping the composite blank 10 between a relatively deep intaglio die A and a flat-back die B. The die A is of such form as to produce the stamping 11 illustrated in Fig. 6. Said stamping has a central concave recess 12 defined by two parallel ridges 13. At the outer sides of the ridges 13 are curved surfaces 14 which may, if desired, have emblems or ornamentation impressed thereon by the die A. The ends portions 15 of the stamping 11 are of the desired width and cross-sectional form to constitute the finger band.

25 Preliminary to the stamping operation, the composite blank 10 is laid on the intaglio die A with the flat side of the composite blank (i. e., the gold sheet 1) in contact with the intaglio die. The flat-back die is then driven down against the composite blank, whereby the sheet 1 is forced into the die A to form a stamped gold shell, the filler piece 5 is transformed into the shape indicated in Figs. 5 and 6, and the edge portions of the blank 1 are bent up around the edges of the parts 5 and 9. The filler piece 5 is of such form and mass as to fill completely the stamped gold shell between the end-pieces 9 without causing the thin sheet 1 to be ruptured as it is being drawn down into the cavity of the die A.

30 The flat-back die B imparts to the upper side of the composite blank or forging 11 the flat form shown in Fig. 5.

The mass of the silver filler piece 5 is such that a considerable portion thereof overflows the sheet

or shell 1 in the stamping operation, as will be understood from Fig. 6; in this view the excess silver and gold is indicated at 16. The next step consists in removing the overhanging portion or flash 16 by trimming or any other suitable method.

In any drawing or stamping operation, whether the intaglio die be shallow or deep, the metallic sheet will stretch and become thinner towards the edge of the cavity of the die. If the sheet be thin originally, the stretching and thinning of the sheet during the stamping operation will cause the sheet to become excessively thin or rupture in the region towards the edge of the cavity of the die. It is, however, very desirable to conserve gold by using a thin sheet. In order to be able to use a thin sheet, and to avoid the effects of the inevitable thinning, I use a relatively deep die A so that the part of the stamping or forging which I wish to employ in the manufacture of the ring will be below the level at which the thinning occurs. This will be best understood by reference to Fig. 7, where the region in which thinning occurs is indicated at a.

25 The formed blank or forging 11 so produced is considerably thicker than is required. The next step, therefore, consists in removing the excess thickness by milling or grinding away the material indicated by the bracket b and the 30 dotted line c. It will be noted that the line c is below the region where thinning has taken place.

Fig. 8 illustrates the blank 17 thus obtained. The flat side there shown is the flat surface produced by the milling or grinding operation. 18 35 indicates the edge of the thin gold shell that encloses or surrounds the silver filler piece 5 and the gold end-pieces 9. The milling operation incidentally removes the greasy film usually present on a stamping, so that the flat surface shown 40 in Fig. 8 is clean and ready for the next operation. The milling operation also enables me to produce a blank 17 of predetermined thickness and hence of predetermined gold content.

After extended use, the working surface of the 45 die B becomes somewhat uneven, thus imparting an uneven surface to the side of the stamping 10 shown uppermost in Fig. 5. Such an uneven surface would be unsuitable for the next operation, but it is, of course, removed in the milling 50 operation, thus making it possible to use the die B much longer than would be practicable if my method did not include the use of a deep die and the milling operation.

55 Preferably the inner circumference of the completed ring is formed of a gold overlay 19 punched from a thin gold sheet. The overlay 19 is somewhat wider than the blank 17. The overlay is soldered, fused or welded to the flat milled side of the blank 17, after which the excess width of 60 the overlay is removed. There is thus produced the composite blank 20 shown in Fig. 10.

The next operation consists in bending the composite blank 20 into the form of a finger ring, as indicated in dotted lines in Fig. 10. The bending of the blank converts the concave recess 12 65 into a flat seat upon which a stone or emblem may be mounted.

70 The use of the sheet 1, which is of rolled material, contributes to the attainment of a predetermined gold content, since such a sheet is of uniform density.

In the following claims the term "milling" is used to denote any equivalent method of removing the excess thickness of the stamping 11, and 75 the term "soldering" is employed to designate

soldering, welding or other equivalent method of securing metallic parts together.

I claim as my invention:

1. The method of making a bimetallic finger ring which consists in punching a thin flat blank from a thin sheet of gold, said blank having a central portion and two end portions extending in opposite directions from the central portion; making a silver filler piece consisting of a middle portion having a central hump and a relatively slender portion at each end of the middle portion; making two gold end-pieces corresponding generally in width to the width of said slender portions of the filler piece; securing the filler piece and the end-pieces to the flat gold blank, 10 the width of the gold blank being greater than that of the filler and end pieces; stamping the composite blank thus produced between an intaglio die and a flat-back die, the flat gold blank 15 being placed in contact with the intaglio die, the stamping operation serving to bend the margin of the gold blank over the edges of the filler and end pieces, such bending causing thinning in the bent marginal portions of the gold blank; milling the flat side of the stamping thus produced 20 to reduce its thickness to a plane below the level at which thinning of the gold blank has occurred in the stamping operation; securing a gold overlay to the milled side of the stamping; and bending the composite blank thus obtained into the 30 form of a finger ring.

2. The method of making a bimetallic finger ring which consists in punching a thin flat blank from a thin sheet of gold, said blank having a central portion and two end portions extending 35 in opposite directions from the central portion; making a silver filler piece consisting of a middle portion having a central hump and a relatively slender portion at each end of the middle portion; making two gold end-pieces corresponding 40 generally in width to the width of said slender portions of the filler piece; securing the filler piece and the end-pieces to the flat gold blank, the width of the gold blank being greater than that of the filler and end-pieces, stamping the 45 composite blank thus produced between an intaglio die and a flat-back die, the flat gold blank being placed in contact with the intaglio die, the stamping operation serving to bend the margin of the gold blank over the edges of the filler and 50 end pieces, such bending causing thinning in the bent marginal portions of the gold blank; milling the flat side of the stamping thus produced to reduce its thickness to a plane below the level at which thinning of the gold blank has occurred in 55 the stamping operation; and bending the stamping into the form of a finger ring.

3. The method of making a bimetallic finger ring which consists in making a thin flat blank from a thin sheet of gold, said blank having a central portion and two end portions extending 60 in opposite directions from the central portion; securing to the flat gold blank a body of metal which is to be enclosed by said blank, the width of said blank being greater than that of said body of metal; stamping the composite blank thus produced between an intaglio die and a flat-back die, the flat gold blank being placed in contact with the intaglio die and being bent in the stamping operation into the form of a shell 70 containing said body of metal, the stamping operation serving to bend the margin of the gold blank over the edges of said body of metal, such bending causing thinning in the bent marginal portions of the gold blank; milling the flat side 75

of the stamping thus produced to reduce its thickness to a plane below the level at which thinning of the gold blank has occurred in the stamping operation; and bending the stamping into the form of a finger ring.

5. 4. In the manufacture of bimetallic finger rings, the method which includes making a composite finger-ring blank, one side of which consists of a gold sheet, laying the blank on an intaglio die with the gold sheet in contact with said die, forcing the blank against and into said die with a flat-back die, whereby that portion of the
- 10

gold sheet which is forced into the cavity of the intaglio die is drawn to greater thinness in the region adjacent to the edge of the cavity of the intaglio die, and then milling off the flat side of the stamping thus produced to a plane extending through the portion of the stamping previously received within the cavity of the die and below the level of the thinnest part of said gold sheet, thereby retaining only the thicker part of said gold sheet in the stamping.
